UNITED STATES PATENT OFFICE.

WILLIAM AITKEN AND ROBERT AITKEN, OF LONDON, ENGLAND.

SEMI-AUTOMATIC TELEPHONE-EXCHANGE SYSTEM.

1,195,891.

Specification of Letters Patent. Patented Aug. 22, 1916.

Application filed December 23, 1914. Serial No. 878,761.

To all whom it may concern:

Be it known that we, WILLIAM AITKEN and ROBERT AITKEN, subjects of the King of Great Britain and Ireland, residing in London, England, have invented certain new and useful Improvement in Semi-Automatic Telephone-Exchange Systems, of which the following is a specification.

This invention relates to telephone systems and more particularly to manually operated or semi-automatic telephone systems in which the junctions, or exchange interconnecting lines, are worked automatically without the use of, (or, in certain cases very limited use of) dial, push-button, or other pattern of keyboard calling device. By such an arrangement the operator's work would be similar to the present manual methods. The plugging into a jack however would select an idle junction line appropriate to the connection to be built up, and connect an automatically operated or machine-driven impulse sending device which would interrupt the circuit intermittently according to a code which will operate selectors, or other automatic switches, to call an operator at the exchange wanted.

The invention is illustrated by three sheets of drawings in which:—

Figure 1 shows a typical lay-out of a large telephone area. Fig. 2 a diagrammatic representation of the circuits through certain exchanges of such an area. Fig. 3 is a section of a machine-driven impulse-sender. Fig. 4 an elevation of the same. Fig. 5 a diagram of one arrangement of circuits for the above impulse-sender.

In a large telephone area as represented in Fig. 1 for economical reasons it is advisable to utilize junctions having a light gage of copper for conversation between adjacent exchanges when they are only a short distance apart, or between groups of local exchanges, medium gage when the exchanges are farther apart, or the conversation is through two or more intermediate exchanges, and heavy gage copper when the exchanges are on the opposite sides of an area and for connections to the trunk or "long distance" exchange. In such an area it would be impossible for operators to correctly route and select the proper gage of wire for through connections and it is the object of this invention to do this automatically without the knowledge or assistance of the operator.

In Fig. 1, C represent exchanges in the center of the area, T the trunk exchange. W S N and E are large exchanges which also fulfil the part of junction line connecting exchanges, and around these are grouped subordinate exchanges. Around the fringe of the area are shown small exchanges designated by M which are not important enough in all cases or have not proper facilities to warrant the introduction of machine-driven impulse-senders. Between certain exchanges, as for example W¹ and M, only light gage wires are shown as available. It is reckoned that the short length of light gage would not appreciably depreciate the transmission, say when through to the trunk exchange because heavy gage wire would be utilized beyond W¹. M talking to M¹ might still utilize light wires, when talking to W⁵ might use medium gage, and when talking to trunk or central and beyond would use heavy gage wires. Exchange W has light gage wires to talk to the central, medium to talk to N or S and exchanges immediately connected therewith, and heavy wires for connections beyond these and to the trunk exchange. Exchanges W², S², E⁶ and others similarly situated are shown with all three gages to allow them good facilities for reaching all exchanges in the area. In an area laid out in this way it is not necessary to run direct lines to different exchanges from one point as is the practice at present. The junctions should run from exchange to exchange only and be multiplied on the banks of selectors or other automatic switches so as to be available to a large number of exchanges. Connections to the trunk exchange from outlying exchanges would be obtained through the junction centrals C, N, S, E, W. Where an instantaneous service is given over a large number of long junctions or trunks arrangements can be made for calling through the trunk exchange and building up a continuous circuit to an exchange beyond by fitting a repeater or intermediate impulse sending device, which would send out additional impulses or repeat a desired code.

Fig. 2 shows the switching arrangements, circuits however being represented by single lines. Exchange W¹ is the exchange selected to illustrate our invention. At W¹ is shown a multiple board consisting of a multiple of three sections, three lines being shown in each multiple in the length and

four multiples for junction lines in the height and a level of multiples for subscribers' lines. The signaling circuits only are shown, and the circles indicate the bush 5 of the jacks on which they end. P to P² represent incoming junctions from small outlying exchanges, and P³—P⁴, P⁵—P⁶ are plug units for connecting subscribers' lines to outgoing junctions or jack ending 10 lines from small exchanges to outgoing junctions. IS¹ to IS⁷ are impulse senders one being associated with each outgoing junction line. These are machine-driven and electrically controlled in such a way that 15 when a plug is inserted in a jack a disk revolves and opens the line circuit a predetermined number of times to actuate an automatic switch at a distance. These will be described more in detail later. S to S² are 20 subscribers' lines which have signaling lamps L¹¹ to L¹³ and terminate on multiple jacks J¹¹ to J¹³. Above W¹ is shown apparatus located at several exchanges the designating letters corresponding to the letters in Fig. 1. The automatic switch represented is of the Strowger type with vertical and rotary movements. A side view is indicated so that the horizontal lines represent bank levels in which there are usually ten 25 circuits. All circuits on a level are of the same gage conductor but different levels may have different gages. a is the shaft carrying the wipers b which make contact with the bank contacts c. Firm lines in 30 Figs. 1 and 2 indicate heavy gage circuits, dot and dash lines medium conductors, and dotted lines light gage circuits. M¹ represents a small manual exchange in which connections may be obtained over a direct circuit J¹ to W¹ where the connection would be manually completed and the remainder built up automatically. M¹ has an alternative arrangement, an impulse-sender of the dial, push button or other type being fitted 35 so that the operator can call automatically and build up any connection desired. M represents a small exchange which has no automatic apparatus whatever, the operator taking the demands orally and W¹ making 40 connections which build up the remainder of the connection automatically. W² is an exchange having machine-driven impulse senders. The junction line JL is shown connected to two impulse-senders IS⁸ and IS⁹, 45 and to two jacks J⁶, J⁷ in parallel. It is supposed that there are only a small number of junction lines available and that a large proportion of the calls are to two exchanges, for example, W¹ and trunk T. The two 50 senders have different codes so that if the operator inserts the plug in jack J⁶ she will connect with W¹, but if the plug is inserted in jack J⁷ the trunk exchange will be called. Three or more exchanges may be called over 55 one wire in the same way.

Jacks and impulse-senders and some connection with an automatic line switch will be provided for every exchange that may be connected with, but only junctions sufficient to carry the traffic will be necessary, 70 these being subdivided according to the traffic to exchanges having light, medium and heavy gage junctions. The jack or multiple of jacks associated with an exchange will be suitably labeled with the code of the exchange although it has no direct circuit thereto. For example, if subscriber S of W¹ calls for a number in exchange M⁷, the operator, having already inserted the plug P³ in J¹¹ to answer, inserts P⁴ in jack M⁷. 75 The line switch of the Strowger type would connect with a preselected idle junction of a group having all lines of a particular gage of conductor. The impulse-sender which may be connected in parallel with the line switch or be in a local circuit completed by it will also be energized and open the circuit according to a code (to be described later) to cause the shaft a of a selector W¹⁰ at the exchange W to lift the wipers b, in 80 this case to the fourth level. The wipers then rotate automatically to select an idle line and make contact with the bank spring c. The line is thus extended to the exchange N where the selector acts in a similar manner again rising to the fourth level, according to the predetermined code of the sender, and the line is further extended to N¹ where the wipers make contact on the first level. 85 N⁴ is next operated and connects with the 100 third level when the lamp L⁷ at exchange M⁷ glows as a calling signal. The code on the impulse-sender for M⁷ is 4413. If the jack marked T had been plugged into a heavy gage junction would again have been 105 selected but as the sender code is one impulse W¹¹ at W connects on the first level and the lamp LT glows at the trunk exchange. If jack C is plugged into, the line switch of which is in a group having medium gage junctions to the W exchange, code 1 on W¹² raises it to the first level and the lamp LC glows at C. A connection in exchange W may be obtained by the line switch at W¹ connected to jack W glowing 110 a lamp directly at W, or a selector W¹³ be raised to the fifth level to glow the lamp. M⁹ is called in a manner already described the code being 341. If M¹⁵ is wanted the 115 jack so labeled would be plugged into and the code 2441 would call into exchange E⁶ where a line would be selected in which there is a second impulse sender which would send additional impulses to call into M¹⁵ and glow the lamp L¹⁰, the additional 120 code being 321. Should subscriber S³ on M¹ desire connection with, say C, the operator would insert the plugs P⁷, P⁸ in jacks J, J² and manipulate the dial IS¹⁰ for two 125 digits, or P⁸ would be inserted in J¹ and the 130 digits, or P⁸ would be inserted in J¹ and the 135

operator at W^1 asked to complete the connection by inserting the plug P in jack C . In a similar manner M would connect S^4 by plugs P^9 , P^{10} in jacks J^3 , J^4 and W^1 , plug P^1 in jack C . Lamp L is the calling signal at W^1 for exchange M^1 . S^5 on W^3 would be connected by plugs P^{11} , P^{12} in jacks J^5 and J^6 or J^7 to call into one of two exchanges by means of selector WS .

10 Selectors and line switches of the Strowger type have been described but any other type may be used. The line switches of the type which finds the calling line might advantageously be used preferably located at the originating exchange with branch lines 15 between the jacks and the bank contacts so that the switch would pick out the operator calling, in a well-known manner. The manual exchanges referred to may be of the 20 common battery type where the operator disconnects on the two supervisory signals being displayed, or they may be of the type in which the cords are rendered electrically 25 inoperative or disconnected when the calling, or calling and called subscribers replace the receivers after conversation.

All or some of the exchanges may be 30 equipped with automatic apparatus so that for incoming calls the subscriber wanted may be called by the operator at the originating exchange or other controlling exchange manipulating a dial or other form of impulse sender, or may be called by the calling subscriber manipulating such a calling 35 device which is fitted in connection with his instrument. In such an arrangement the subscriber would lift the receiver to glow a lamp as a calling signal as at present, and give the operator the name only of the exchange 40 wanted. The operator by inserting the plug in the jack associated with that exchange would automatically connect with that exchange by the machine-driven impulse-sender, when the calling subscriber 45 then dialing the number wanted would complete the connection by operating selectors, and a connector in the terminal exchange in the well-known manner.

Figs. 3 and 4 show one method of construction of our automatically operated or 50 machine-driven impulse-sender and Fig. 5 shows the same in diagrammatic form associated in one way with a line switch of the Strowger type and the connections with the 55 jacks on one side and the junction line on the other. 20 is a fixed coil with a core 21 carried by brackets 25 and 31. An iron sheath 22, 23 forms the magnetic return which is free to rotate, the rear part 23 being formed as a driving wheel rotatable on the fixed shaft 24. 30 is an impulse wheel rotatable on a shaft 32. The spring 29 has one end secured to the core 21 and the other end to the wheel 30 and is so arranged that 65 it keeps the wheel 30 normally away from

the core and also returns it to normal after rotation. The wheel 30 is normally out of line of engagement with the springs 34 but when the coil 20 is energized the wheel 30, which is wholly or partly of iron, is attracted, but is kept from making actual contact with the sheath 22 or the core 21 by non-magnetic stops 33. A power-driven shaft 26 by the pinion 39 rotates the sheath 22, 23 and the wheel 30 is now carried around so 70 that the teeth 36 engage with the brush or wheel 35 which is raised when passing over the teeth so as to close the contact 43—44 and open the contact 45—46, so that the circuit is interrupted according to the code of 75 the wheel which as shown is 4413. After all the teeth have been passed over the pin 37 opens the contact 38—42 and the contact of the pin 37 with the heavy spring 40 brings the wheels to rest. The opening of the contact 38—42 puts the resistance 49 (Fig. 5) in 80 circuit to reduce the current and to enable the wheel 30 to slip readily on the sheath 22 which is still rotating. When current is removed from the coil 20 the spring 29 forces 85 the wheel 30 away from the core so that it does not engage with the springs 34 on counter-rotation, and returns the wheel to the normal position. A number of these senders 90 may be fitted on a common shaft and they 95 may be fitted for one shaft driving two rows as shown by the second wheel 41. In busy exchanges these may be continuously rotated during busy hours but during quiet hours and in small exchanges they may be controlled by a master magnet or other well-known device so that they start when the plug is inserted.

In Fig. 5 P is a plug ending a junction or may be the calling plug of a pair. It is 105 only necessary to show the circuit of the third conductor which is connected through resistance 51 to battery 48 and earth. A junction line 61, 62 is shown with a multiple of three jacks M^7 . The bush wire of the 110 jacks is carried in parallel through the coils of the impulse-sender 20 and the line switch 52 to earth. The multiple wires 63, 64 are carried to short-circuiting springs 43, 44, and to opening springs 45, 46. The former 115 reduce the resistance of the circuit and prevent disagreeable clicking in the caller's receiver. The latter interrupt the circuit so as to allow the automatic switches to be actuated. The wires are extended to springs 120 on the line switch which are normally open. When the armature 53 is attracted the plunger 54 forces its insulated end 55 between the springs 57, 60 so that one wire is joined through by springs 56, 57 and the other by 125 springs 58, 59. When the plug P is inserted in a jack M^7 and the sleeve 47 makes contact with the bush the circuit is shown through the two coils 20 and 52 in parallel. The circuit might be through 52 only, winding 20 130

being connected in a local circuit completed by the line switch.

The apparatus and circuits specified are given merely by way of example it being obvious that many modifications may be made.

What we claim and desire to secure by Letters Patent is:—

1. In a telephone system, an exchange, a plurality of other exchanges, junction lines connected to said first-mentioned exchange over which connection may be made with said other exchanges, an automatic numerical switch for selecting said junction lines, a plurality of jacks whereby connection may be made with said automatic switch, each of said jacks having associated with it means for sending a particular numerical call so as to connect only with a particular junction line or lines through said automatic switch.

2. In a telephone system, a calling subscriber's line connected to one exchange, a plurality of other exchanges, a called subscriber's line connected to one of said other exchanges, an intermediate exchange through which connection is completed from said calling subscriber's line to said called subscriber's line, junction lines connecting said intermediate exchange to said other exchanges, a numerical automatic switch at said intermediate exchange, jacks at said first-mentioned exchange, a junction line leading from said jacks to said automatic switch, an automatically operated calling means associated with said jacks and arranged so that the plugging into any particular one of said jacks determines the numerical operation of said automatic switch and thereby the junction line selected leading from said intermediate exchange to the one of said other exchanges to which the called subscriber's line is connected.

3. In a telephone system, a calling subscriber's line connected to one exchange, a plurality of other exchanges, a called subscriber's line connected to one of said other exchanges, an intermediate exchange through which connection is completed from said calling subscriber's line to said called subscriber's line, junction lines connecting said intermediate exchange to said other exchanges, a numerical automatic switch at said intermediate exchange, groups of jacks at said first-mentioned exchange, groups of junction lines leading from said first-mentioned exchange to said intermediate ex-

change, each group of junction lines being associated with one of said groups of jacks, non-numerical automatic switches associated with each of said groups of jacks and adapted to connect a jack plugged into with an idle junction line of the corresponding group of junction lines, automatically operated calling devices associated with said jacks and arranged so that the plugging into any particular one of said jacks determines the numerical operation of said automatic switch and thereby the junction line selected leading from said intermediate exchange to the one of said other exchanges to which the called subscriber's line is connected.

4. In a telephone system, a calling subscriber's line connected to one exchange, a plurality of other exchanges, a called subscriber's line connected to one of said other exchanges, an intermediate exchange through which connection is completed from said calling subscriber's line to said called subscriber's line, junction lines connecting said intermediate exchange to said other exchanges, a numerical automatic switch at said intermediate exchange, groups of jacks at said first-mentioned exchange, groups of junction lines leading from said first-mentioned exchange to said intermediate exchange, each group of junction lines being associated with one of said groups of jacks, the different groups of junction lines being of different gage wire, non-numerical automatic switches associated with each of said groups of jacks and adapted to connect a jack plugged into with an idle junction line of the corresponding group of junction lines, automatically operated calling devices associated with said jacks and arranged so that the plugging into any particular one of said jacks determines the numerical operation of said automatic switch and thereby the junction line selected leading from said intermediate exchange to the one of said other exchanges to which the called subscriber's line is connected.

In testimony whereof we have affixed our signatures in presence of two witnesses.
